UNITED STATES PATENT OFFICE.

ALBERT H. NELLER, OF FAIRFIELD, IOWA, ASSIGNOR TO LOUDEN MACHINERY COMPANY, OF FAIRFIELD, IOWA, A CORPORATION.

CATTLE-STALL.

1,072,352.

Specification of Letters Patent.

Patented Sept. 2, 1913.

Application filed November 8, 1910. Serial No. 591,351.

To all whom it may concern:

Be it known that I, ALBERT H. NELLER, a citizen of the United States, residing at Fairfield, in the county of Jefferson, State 5 of Iowa, have invented a new and useful Improvement in Cattle-Stalls, of which the following is a specification.

My invention relates to stalls principally intended for holding calves when being fed 10 and for other purposes, and it consists of an improvement whereby the members constituting the stanchions used may be operated separately or simultaneously and be readily adjusted to different sizes of calves. 15 Also, in certain details of construction described in the specification and more specifically set forth in the claims.

In the accompanying drawing forming a part of this specification, Figure 1 is a side 20 view of a section of cattle stalls embodying the features of my invention. Fig. 2 is an enlarged transverse section on line 2—2 of Fig. 1. Fig. 3 is the same on line 3—3 of Fig. 1. Fig. 4 is an enlarged detail view 25 which will be hereafter explained. Fig. 5 is an enlarged transverse section on line 5—5 of Fig. 1. Fig. 6 is an enlarged transverse section on line 8—8 of Fig. 1.

Referring to the drawing, A and A' represent 30 two upright posts set in a concrete floor.

B and B' represent two horizontally disposed bars, preferably of tubular metal, joined at each end to the posts A and A'. 35 The bar B is connected to the posts near their upper ends and the bar B' near their lower ends, a sufficient distance above the floor to permit cleaning under it.

C and C' represent a series of vertically 40 disposed bars, preferably of tubular metal, spaced apart and connected at their upper and lower ends to the bars B and B' by means of clamps preferably composed of two parts D held together by bolts passed 45 through the parts D at the sides of the bars C.

The stanchion members for holding the calves or other cattle are represented by E and E'. These members, which are also 50 preferably of tubular metal are pivotally connected at their lower ends to the lower bar B' by means of clamps composed of two parts F held together by bolts G and H, the former of which, as shown in drawings 55 (most plainly in Fig. 3), passes through a

hole in the lower end of the members E and E'. The upper ends of the stanchion members are fitted with a pair of mating castings I, held together by bolts J. The central portions of the castings I are spread apart to form an oblong opening between them to admit the upper bar B and to permit them to slide back and forth thereon. The lower bolt J is preferably passed through a hole in the upper end of the members E and E'. The upper ends of the castings I are extended above the upper bolt J and are recessed and cut away to receive a horizontally disposed slidable bar K, and a latch piece L which is adapted to drop into 60 notches k and k' in the upper edge of the bar K adjacent to the castings I.

M is a link pivotally connected at one end to the bar K and at the other end to a lever N.

The upper end of the bar C' is fitted with a special clamp composed of pieces O having upper and lower bolts P and Q, (see Fig. 5). The bolt P is passed through a hole in the upper end of the bar C' and 65 the upper bolt Q is passed through the upper ends of the pieces O a little above the bar B. The upper ends of the pieces O are spaced apart, and a triangular shape plate R preferably made U shaped in vertical 70 cross section, is inserted between said upper ends and is held in place by the bolt Q. The central portion of the lower or doubled side of the plate R is preferably cut away so that the outer lower portions will rest upon the upper side of the bar B and be braced and held in rigid position thereby. The lower end of the lever N is pivoted to the 75 upper end (or ends, if doubled,) of the plate R, as most plainly shown in Figs. 4 and 5. 80 The latch pieces L having their lower ends inserted in the adjacent notches k or k' in the bar K, the movement of the lever N will cause the castings I to slide back and forth on the bar B, and the upper ends of the 85 stanchion members will be rocked back and forth thereon. The latch pieces L being inserted in the notches k and the lever N being raised, the upper ends of the stanchion members E will be brought close to 90 the upper ends of the bars C at the left, and the spaces between said stanchion members and the adjacent bars C at the right will be widened. A bucket of milk or other 95 feed being placed opposite these spaces on 100

105

110

one side of the stall section, the calves on the other side will put their heads through these widened spaces. The lever N being pushed to the right until its free end is a little below the level of the bar K, the stanchion members E will be locked in closed position (as shown by dotted lines) and the calves will be held thereby. If the latch pieces L were all dropped in the notches k', as the one in the center is, the upper ends of the members E would be drawn close to the uprights C at the right when the lever N is pushed down to the right (as shown by central dotted line) and when the lever is raised the members will be brought to their central or closed position as shown by the central member E' in Fig. 1. In this case the calves would be held on the left hand sides of the stanchion members instead of the right. Should it be desired to operate the members in this way some means would be required to hold the lever N locked while in raised position to prevent the opening of the stanchions. The principal use, however, of this arrangement will be to prevent the calves from getting into wrong places. Suppose a weakly calf required some specially prepared food, the stanchion member where this food is placed could be set with its latch piece in the notch k' and when the other stanchions were opened this one would be closed. The strong calves would rush into the open stanchions which would then be closed. This would open the special stanchion for the weak calf and as soon as it was in place the stanchion member could be closed by shifting the latch piece L from the notch k' to the notch k. The latch piece L is preferably made with a rounded head to facilitate lifting it out of the notch in the bar K. Also, with a T on its lower end to prevent it from getting out of the recesses i in the upper ends of the castings I.

It is important that the uprights C be made adjustable on the bars B and B', especially those next the stanchion members, so that the width of the space between the stanchion members and adjacent uprights may be adjusted from time to time to fit the size of the calves. This requirement is provided for by connecting the uprights C to the bars B and B' by the clamp pieces D. All that is necessary is to loosen the bolts d (see Fig. 6), and slide the uprights along the bars B and B' to the desired point, and then tighten the bolts to hold them there. The lower ends of the stanchion members may also be adjusted along the bar B' so that the spaces between them and the adjacent uprights may be narrower or wider and a larger or smaller number of stanchions may be used in a given section, according to the size of the calves. When this is done additional notches will have to be

made in the slide bar K to correspond with the changed width of the stanchions.

The posts A and A' instead of being set in concrete, as shown, may be joined to the top of the floor in any suitable manner. The free end of the lever N is preferably bent to one side so that it may be pressed down to the level of the bar K without coming in contact with the upper end of the post A. It is also preferable to use two pieces for the link M and rivet one on each side of the lever N and on each side of the end of the bar K. In this way, when the lever is pressed down the pieces M will bind on both sides of the plate R and will help to hold the lever in locked position. The bars B and B' may be connected to the posts A and A' in any suitable manner, but it is preferable to use two part coupling secured together by bolts as shown in Fig. 1. The bars B and B' and the upright C at the left of the post A' are parts of an adjoining section of stalls.

What I claim is:

1. In cattle stalls, the combination of vertically disposed posts secured to the floor, horizontally disposed bars having their ends connected to said posts, one near the upper ends of the posts and the other near their lower ends above the floor, a series of upright bars spaced apart and adjustably secured at their upper and lower ends to said horizontal bars, a stanchion member pivoted at its lower end to the lower horizontal bar, castings having openings in their upper ends affixed to the upper ends of the stanchion member so as to straddle the upper horizontal bar and adapted to slide thereon, a horizontally movable bar having notches in its body inserted in the openings of the castings, a latch piece mounted in said casting adapted to engage the notches in the movable bar and to be disengaged therefrom, and means to move the bar and lock it in fixed position.

2. In a device of the character described, mating castings having an opening between their upper ends secured to the upper end of a stanchion member suitably pivoted at its lower end, a horizontally movable bar, having notches therein inserted in the opening between the castings, a latch piece mounted between the upper ends of the castings, adapted to engage the notches in the movable bar and to be disengaged therefrom, and means to operate the movable bar and to lock it in fixed position.

3. In a device of the character described, mating castings secured to the upper end of a stanchion member suitably pivoted at its lower end said castings having an opening therebetween, a horizontally movable bar, having notches therein, said bar being received within the opening between said castings, a latch piece mounted between the up-

per ends of the castings, adapted to engage the notches in the movable bar and to be disengaged therefrom, said latch piece having a T at its lower end to fit in recesses 5 in the casting to hold it in operative position, and means to operate the movable bar and lock it in fixed position.

4. In a device of the character described, a stanchion member pivoted at its lower end 10 and connected at its upper end with a horizontally movable bar upright bars on each side of the stanchion member, a latch piece to engage said movable bar and be releasable therefrom, and means to operate the 15 movable bar and to lock it in position so that it may act in conjunction with the upright bar on either side.

5. A cattle stall comprising upright bars, a stanchion member located between said 20 bars adapted to act in conjunction with said bars on either side of the member.

6. In a device of the character described, upper and lower horizontal members spaced apart and the lower member being supported 25 a distance above a floor, a series of upright bars secured at their upper and lower ends to the horizontal members and adjustable on the members by clamps slideable thereon, a series of stanchion members pivoted at their lower ends to the lower horizontal member between adjacent upright bars, a horizontally slideable bar connected to the upper ends of the stanchion members and means to slide the bar and hold it in 35 fixed position.

7. In a device of the character described, upper and lower horizontal members spaced apart and the lower member being supported 40 a distance above a floor, a series of upright bars secured at their upper and lower ends to the horizontal members and adjustable on the members by clamps slideable thereon, a series of stanchion members pivoted at their lower ends to the lower horizontal member between adjacent upright bars, and their upper ends slideable on the 45 upper members, a horizontally slideable bar connected to the upper ends of the stanchion members and means to slide the bar and hold it in fixed position.

8. In a cattle stall comprising upright bars, a stanchion located between said bars adapted to be moved in proximity to and in conjunction with said bars on either side of the member. 55

9. In a device of the character described, vertically disposed posts secured at their lower ends to a floor, upper and lower horizontal members spaced apart and secured to the posts the lower member being a distance 60 above the floor, a series of upright bars spaced apart and secured by clamps slideable on the upper and lower members, and a series of stanchion members pivoted to the lower horizontal members by clamps slideable 65 thereon.

10. A cattle stall comprising upright bars, a stanchion member located between said bars, and means connected to and for actuating the stanchion member whereby the 70 member may act in conjunction with the upright bars on either side of the member.

11. In a device of the character described, vertically disposed posts secured to the floor, horizontally disposed bars connecting said 75 posts a distance above the floor, a series of vertically extending bars connecting said horizontal bars, stanchion members pivoted to one and slideable on the other of said horizontal members, a horizontal rod connecting 80 the slideable ends of said stanchion members leaving an open space above the upper horizontal member, a lever pivoted to one of said vertically disposed bars, a link connecting said lever and said rod, means whereby said 85 stanchion members may be adjusted on said rod and means to hold said stanchion members in an adjusted position.

12. A cattle stall comprising upright bars, a stanchion member located between said 90 bars, means for actuating the stanchion member, and means connecting the stanchion member to said means whereby the member may act in conjunction with the upright bar on either side of the member.
